UNITED STATES PATENT OFFICE.

MAURICE L. POWERS, OF NEW YORK, N. Y.

DESIGN FOR A NECKTIE-RETAINER.

SPECIFICATION forming part of Design No. 31,430, dated August 22, 1899.

Application filed July 6, 1899. Serial No. 723,000. Term of patent 7 years.

To all whom it may concern:

Be it known that I, MAURICE L. POWERS, of the city of New York, borough of Manhattan, State of New York, have invented a new and 5 original Design for a Necktie-Retainer, of which the following is a full, clear, and exact description, reference being had to the accompanying drawings, forming a part thereof.

In the drawings, Figure 1 represents a front 10 elevation of the necktie-retainer, and Fig. 2 a side elevation of the necktie-retainer.

As is shown in the drawings, the leading or material feature of my design consists of a bulbous terminal or sphere B at the end of a 15 gold wire bent to form a heart shape A, continuing through the center of the heart and at an acute angle at the base of the heart, the single rod which continues through the

heart and almost to the end of it being then bent at right angles and set at its end with a 20 bulbous terminal or sphere B, said bulbous terminal or sphere extended.

It is apparent that this design is also applicable to a scarf-catch and similar articles of jewelry. 25

Having described my invention, what I claim as new, and desire to secure by Letters Patent, is—

The design for a necktie-retainer, as herein shown and described. 30

In testimony whereof I affix my signature in the presence of two witnesses.

MAURICE L. POWERS.

Witnesses:

DAVID WARFIELD,
BELLE C. MILLER.
